(57) **CLAIM**

The ornamental design for a vehicle tire tread, as shown and described.

DESCRIPTION

FIG. 1 is an outside perspective view of a vehicle tire tread showing our design, it being understood that the depicted tread pattern extends over the entire circumference of the tire;

FIG. 2 is an outside elevational view of the vehicle tire tread design shown in FIG. 1;

FIG. 3 is an inside elevational view of the vehicle tire tread design shown in FIG. 1;

FIG. 4 is an outside perspective view of a second embodiment of the vehicle tire tread design shown in FIG. 1;

FIG. 5 is an outside elevational view of the second embodiment of the vehicle tire tread design shown in FIG. 4; and, FIG. 6 is an inside elevational view of the second embodiment of the vehicle tire tread design shown in FIG. 4.

In the drawings, the evenly spaced broken lines illustrate portions of the vehicle tire tread that form no part of the claimed design. The dash/dot/dash broken lines depict the boundary of the claim and form no part of the claimed design.
